SAMPLING SUB WITH REMOVABLE
CUTTING COLLECTORJames N. Gregory, Fullerton, Calif., assignor to
Shell Development Company, San Francisco,
Calif., a corporation of Delaware

Application October 31, 1950, Serial No. 193,189

11 Claims. (Cl. 255—1.4)

1

The present invention relates to apparatus for drilling and coring or logging wells and pertains more particularly to apparatus for collecting samples of formation cuttings from a stream of drilling fluid at a point near a drill bit during rotary drilling.

During well drilling operations, a well may be logged by studying the earth cuttings as they return to the top of the well in the circulating stream of drilling fluid. The fluid is either run through a screen upon which the cuttings are collected, or a sample of fluid is periodically taken from the drilling fluid stream, ditch or pit, and the cuttings contained therein are later separated from the fluid in a laboratory. The main disadvantages of collecting samples of bit cuttings at the top of the well is that the cuttings are generally small in size and have been contaminated by being carried in the stream of drilling fluid for as long as an hour or more. It is furthermore difficult to correlate the cuttings with the particular depths to which they belong.

Thus, in order to obtain relatively large, uncontaminated samples of the formation being traversed by a borehole, it is generally necessary to resort to bottom-hole or side-wall coring. These methods of coring, while normally adequate, result in considerable loss of time in that drilling operations must be stopped while a core is taken. Additionally, side-wall samples obtained by conventional apparatus are often inadequate for microfaunal determination because microfauna specimens occur in streaks which are often missed by taking spot core samples.

Sampling devices for obtaining bit cuttings from the bottom of a borehole usually have the drawback of being fixedly secured to the lower portion of a drill string, necessitating the shutting down of drilling operations and the raising of the entire drill string to the surface for the removal of the cuttings from the sampling device.

It is therefore a primary object of the present invention to provide apparatus for continuously obtaining samples of relatively large size bit cuttings from the circulating drilling fluid.

It is also an object of this invention to provide apparatus for continuously obtaining uncontaminated samples of earth or cuttings near the bottom of a borehole directly after they are washed away from the drill bit.

Another object of this invention is to provide a novel type of sampling sub adapted to contain a sampling device for continuously receiving bit cuttings, said sub being provided with conduit means for permitting the flow of drilling fluid

2

therethrough while sample cuttings are being obtained.

These and other objects of this invention will be understood from the following description of the invention as shown in the accompanying drawing, wherein:

Figures 1 to 4 are views, partly in cross section, of different embodiments of the present apparatus, comprising a sampling device positioned in a special sub or section of a drill string.

Figure 5 is a cross-sectional view taken along the line 5—5 of Figure 1.

Figure 6 is a cross-sectional view taken along the line 6—6 of Figure 3.

Figure 7 is a view in front elevation of a closure sleeve or plug adapted to be lowered into the special sub in place of a sampling device.

Figure 8 is an isometric view of a removable liner adapted to fit within the chamber of a sampling device.

Figure 9 is a view, taken in cross section, illustrating the present sampling device and its associated sub positioned in a drill string at the bottom of a well borehole.

Referring to Figure 1 of the drawing, the present sampling apparatus comprises an elongated tubular member 10 having fixedly positioned in its bore 11 suitable container means such as a holder 12 for positioning a sampling device or cutting collector 13 therein. The tubular member 10, otherwise known as a sub or short section of drill pipe or drill collar, is threaded at its upper and lower ends 14 and 15, respectively, whereby the upper end 14 may be connected to a section of drill pipe or a drill collar 16, and the lower end 15 may be connected to another section of the drill pipe or to a bit 17. The special sub 10 is preferably connected into the drill string 16 directly above a wall scraper or drill bit 17, as shown in Figure 9, but it is understood that the present sub may be connected between any two sections of the drill string.

The tubular member 10 is provided with one or more slots or ports 18 through the wall 19 thereof to permit earth cuttings to enter the bore 11. Preferably, the axis of the slot 18 slants downwardly to permit any cuttings entering the slot 18 to slide into the bore 11. However, the walls of the slot may have any other slant (or may extend horizontally, as shown in Figure 9). Preferably, the slot 18 is located near the upper end of the sub 10 and may be of any size desired. However, the slot opening should have an area of several times the size of the cuttings which it is desired to collect. If desired, an annular re-

cess 20, having a width at least equal to the length of the slot 18, may be cut in the outerwall of the tubular member 10 at the level of the port or ports 18. The purpose of this annular groove or recess 20 will be explained hereinafter.

The axial bore 11 of the sub 10 is normally of the same diameter as the bore of the drill string 16. The holder 12, which may be formed of a tubular member open at its upper end 21 and preferably closed at its lower end 22, is fixedly supported in a preferably coaxial manner in the bore 11 of the sub 10 by support members 23 and 24, seen in Figure 1, or 25 and 26, seen in Figure 5. The holder 12 is provided near its upper end with a longitudinal slot or window 27 through the wall thereof, said slot 27 being preferably equal in size to the slot 18 in the sub 10, to permit earth cuttings to pass readily therethrough and into a container 13 carried within the holder 12. The supports 23, 24, 25 and 26, which may be welded to both the inner wall of the sub 10 and the outer wall of the holder 12, form a short conduit or fluidtight passage for conducting samples entering the slot 18 in the sub across the annular space between the sub 10 and the holder 12 and through the slot 27 therein. If desired, the supports 23 to 26 and the edges of the slot 27 in the holder 12 may be slanted at substantially the same angle as the walls of slot 18 to facilitate the entrance of cuttings into the collector 13.

Preferably, a small port 29 is drilled in the wall of the sub 10 at a level below the lower end of the holder 12. A similar port 30 is provided in the lower end of the holder 12 and a short section of conduit 31 is inserted through said ports 29 and 30 and welded therein so that the bore 32 of the holder is in communication with the space outside of the sub 10. The conduit 31 is preferably slanted to permit cuttings or debris, which may enter the scabbard 12 when the collector 13 is removed, to drain therefrom.

The sampling device or cutting collector 13 comprises an elongated tubular member closed at both ends to form a chamber 39, the lower end thereof being closed preferably by a removable pointed cap 33. The removable cap 33 facilitates the removal of cuttings from the collector and its pointed shape serves as centering or guide means when the collector 13 is dropped into the holder 12. The upper end of the collector 13 is provided with an enlarged shoulder 34 which is adapted to be seated on the upper edge 35 of the tubular holder 12, as shown in Figure 1, thus supporting the collector within the holder. The collector 13 is provided with one or more windows 36, 37 and 38 which are of such dimensions and are so disposed in the wall of the collector that at least one of them is always in register with the slot 27 in holder 12, whereby earth cuttings may pass through said slot and windows into the chamber 39.

In order to secure a more fluidtight seal between the cutting collector 13 and the inner wall of the holder 12, one or more annular grooves may be cut or formed in the outer surface of the collector 13 to accommodate rings 40 of any suitable packing material. Generally, however, an adequate seal is provided at the point where the shoulder 34 contacts the beveled seat 35.

The top 41 of the cutting collector is provided with an upwardly-extending axial rod 42 on which is mounted a centralizer of any desired type. As illustrated here, the centralizer com-

prises a pair of stop rings 43 and 44 fixedly secured to the rod 42, a pair of collars 45 and 46 slidably mounted on said rod 42 outside of said stop rings and a plurality of leaf springs 47 and 48 tending to expand and thereby maintained in sliding contact with the inner wall of the drill string 16. The upper end of the rod 42 is provided with a fishing neck 49 for removing the cutting collector 13 from the scabbard 12 and drill string 16.

In another embodiment of the present invention (Figure 2), a sub 50 having a sampling window 51 through the wall thereof is provided with a holder 52 eccentrically and slantingly mounted within the bore 53 of said sub 50. The holder 52 is also provided with a window 54 in the wall thereof which is in register with the window 51 of the sub 50 when the holder 52 is affixed, as by welding, to the inner wall of the sub 50. The lower end 55 of the holder 52 is closed to form support means for a sample collector 56 adapted to be contained within the holder. A drain port 57 is drilled in one side of the holder 52 near the bottom thereof so as to register with a drain port 58 in the wall of the sub 50. The lower end of the holder 52 is preferably welded to the sub 50 at the drain port 58.

In order for a cutting collector 56 to enter the holder 52 when said collector is dropped down through the drill string 16, it is essential that the holder be of sufficient diameter, or be so positioned in the bore of the sub 50, that at least a portion of the open upper end 59 of the holder intercepts the axis of the sub bore 53. Thus, with the collector 56 provided with a pointed cap 60 on its lower end and centralizer springs 61 and 62 near its upper end, the collector will be guided into the open end 59 of the holder and will drop into position in the holder as illustrated in Figure 2. Preferably, the bore 53 of the sub 50 is enlarged below the window 51 in the sub, as shown at 63, whereby the holder 52 may be fixedly secured to the inner wall of the sub 50 in a tilted position which positions the upper end of the holder substantially in the center of the sub.

Threadedly secured to the top of the collector 56 is a rod member 64 carrying the centralizer springs 61 and 62 which may be designed to fit within the holder 52, and rings 65 of suitable packing material for forming a fluidtight seal between the collector 56 and the holder 52. While it is not essential that the collector and the holder be in fluidtight engagement, sealing means are preferably employed to prevent any of the drilling fluid flowing down the pipe string 16 from entering the space between the collector 56 and the holder 52 and thus possibly disturbing the flow of cuttings entering windows 51 and 54. The top of the rod member 64 is also provided with a fishing neck 66 similar to the one in the embodiment of Figure 1.

In the embodiment illustrated in Figures 3 and 6, a sub 70 is provided with a pair of diametrically positioned windows or slots 71 and 72 through the wall thereof. A holder 73 is axially mounted in the bore 74 of the sub 70, said bore 74 being enlarged over the portion of the sub adjacent the holder 73 to provide an enlarged annular flow passage for fluid as it flows by the holder. The tubular holder 73 is provided with a pair of diametrically opposing slots 75 and 76 which communicate with the windows 71 and 72 in the sub 70 by a pair of slanting

conduits formed by support plates or members 71, 78, 79 and 80, seen in Figure 3, and 81, 82, 83 and 84, seen in Figure 6. The support plates 77 and 79 are positioned between and engage plates 81 and 83, while support plates 78 and 80 engage plates 82 and 84. The members 77 to 84 are welded to the inside wall of the sub 70 and the outside wall of the holder 73 to form support means for positioning the holder in the center of the sub.

The holder 73 is open at both ends, the upper end 85 being beveled to seat the shoulder 86 of a cutting collector 87 while the lower end 88 is open to allow any material collecting therein to be discharged therefrom. When employing a holder 73 having its lower end open, it may be found desirable to equip the collector 87 with packing rings 89 below its sample receiving slots 90 and 91 as well as packing rings 92 above said slots thereby preventing any flow of fluid up the holder 73 and out its windows 75 and 76.

In another embodiment of the present invention, shown in Figure 4, a sub 100, having a single window 101 through the wall thereof, may contain a holder 102 having one window 103 and adapted to receive a cutting collector 104. The scabbard 102 may be welded to spacer blocks 105, 106 and 107 which are in turn welded to the inner surface of the sub 100.

When a cutting collector 104 is provided with a single window 108, it is necessary to provide suitable orienting means for aligning the collector 104 within the holder 102 so that the windows of each are in register. Hence, the body of the cutting collector 104 may be provided with a longitudinal slot or keyway 109 from which a diverging shoulder 110 slants downwardly on either side of the collector to meet at a point 111. An alignment pin or key 112 is fixedly mounted in the sub body 100 so that it projects horizontally a short distance into the bore 11 thereof. As the collector 104 is lowered into the sub body 100, the projecting pin 112 will ride up the shoulder 110 and cause the collector 104 to rotate in the bore of the sub 100 until the pin 112 and slot 109 are in vertical alignment. In this position the windows 101 and 108 in the sub 100 and collector 104, respectively, are in register.

During drilling operations when no sampling of cuttings is desired, a cutting collector, such for example, as 87 (Fig. 3), may be removed and replaced with a suitable plug or closure means for closing the slots 75 and 76 in the holder whereby a drilling fluid being circulated down the drill string 16 will not by-pass the bit and flow out the slots 75 and 76. As shown in Figure 7, one embodiment of a slot closure means may comprise a tubular member or closure sleeve 115 which is equipped with a seating shoulder 116 near the upper end thereof which is adapted to engage the shoulder 85 at the top of the holder 73. The length of the tubular member 115 is such that the bottom of said member extends below the slots 75 and 76, effectively closing them. The upper end of the closure sleeve 115 is provided with a fishing neck 117 secured thereto by a plurality of spaced lugs 118. Suitable centralizing springs 121 are also secured to the upper end of the sleeve 115.

It is realized that various changes and modifications may be made in the elements described herein without departing from the principles of this invention. As described with regard to the embodiment illustrated in Figure 1, the chamber

39 in the cutting collector 13 may be closed by a removable plug 33 which is secured in any suitable manner, as in screw-threaded engagement, to the bottom of the collector 13. By removing the plug 33, the collected cuttings may be readily removed from the chamber 39. If desired, the collector may be equipped with a removable liner 120 (Figure 8), having an open top and a closed lower end. The liner is formed of a thin material shaped to fit within the annular chamber 39. While a thin metallic liner 120 may be used, it is preferably made of a transparent plastic material whereby the different layers of cuttings, collected from the various strata traversed by the drill bit, may be visually inspected before removing them from the liner. The layers of cuttings in the liner 120 will be arranged in the inverse order in which the strata are penetrated.

The cutting collector is lowered by cable or dropped through the drill string 16 and into position in the sub 10, as shown in Figure 9. If a cable 123 is employed to lower the collector, the cable is withdrawn to the surface before drilling operations are resumed. Drilling fluid being circulated down the drill string 16 passes through the annular space 11 around the holder 12, through the bit 17, and up the annular passageway 124 between the drill string 16 and the wall of the borehole.

The present cutting collector operates on the principle that the velocity of the circulating fluid rising in the annular passageway 124 is reduced when the fluid passes the slot 18 and window 21 in the sub 10 and the sample collector, respectively. An annular recess 20 (Figure 1) in the outer wall of the sub 10 also acts to reduce the velocity of the fluid flow. The resulting decrease in the circulating fluid velocity together with the turbulence created by the slots 18 and 21 reduces the carrying power of the circulating fluid. The earth cuttings, especially the larger and more desirable ones, are thrown out of the mud stream and into the chamber 39 of the collector 13. The collected cuttings may be raised to the surface of the well along with the collector 13, by a fishing tool 122 at the end of a cable 123.

I claim as my invention:

1. Apparatus for collecting earth cuttings from mudflush circulating in a borehole, comprising in combination a tubular member adapted to be connected into a drill string, a tubular holder fixedly carried within the bore of said tubular member co-longitudinally therewith, the outer diameter of said holder being appreciably smaller than the inner diameter of said bore, whereby a fluid passage is formed within said bore about said holder, a hollow cylindrical sample collector slidably fitting within the holder, radial window means through the walls of said collector, ported radial conduit means through the walls of said tubular member and said tubular holder adapted to register with said window means when said collector is inserted in said holder, and fishing head means affixed to the upper part of said collector for raising said collector from said holder.

2. Apparatus for collecting earth cuttings from mudflush circulating in a borehole, comprising in combination a tubular member adapted to be connected into a drill string, a tubular holder open at its upper end and closed at its lower end positioned within the bore of said tubular member coaxially therewith, the outer diameter of said holder being appreciably smaller than the

inner diameter of said bore, whereby an annular fluid passage is formed within said bore about said holder, spider means in said passage fixedly attaching said holder to said member, conduit means through the wall of said tubular member and through the wall of said tubular holder near the lower end thereof, a hollow cylindrical sample collector slidably fitting within the holder, radial windows through the walls of said collector near the upper end thereof, ported radial conduit means through the walls of said tubular member and said tubular holder adapted to register with said windows when said collector is inserted in said holder, and fishing head means affixed to the upper part of said collector for raising said collector from said holder.

3. Apparatus for collecting earth cuttings from mudflush circulating in a borehole, comprising in combination a tubular member adapted to be connected into a drill string, a tubular holder fixedly carried eccentrically within the bore of said tubular member co-longitudinally therewith, the axis of the bore of said tubular member being arranged at an angle inclined to the axis of the bore of said tubular holder, the outer diameter of said holder being considerably smaller than the inner diameter of said bore, whereby a fluid passage is formed within said bore outside said holder, a hollow cylindrical sample collector slidably fitting within the holder, radial window means through the walls of said collector, a ported radial conduit through the walls of said tubular member and said tubular holder adapted to register with said window means when said collector is inserted in said holder, and fishing head means affixed to the upper part of said collector for raising said collector from said holder.

4. Apparatus for collecting earth cuttings from mudflush circulating in a borehole, comprising in combination a tubular member adapted to be connected into a drill string, a tubular holder fixedly carried eccentrically and slantly within the bore of said tubular member substantially co-longitudinally therewith in a manner such that the axis of the bore of said tubular member passes within the periphery of the upper open end of the bore of said holder, said holder being closed at the lower end thereof, the outer diameter of said holder being appreciably smaller than the inner diameter of said bore, whereby a fluid passage is formed within said bore outside said holder, a hollow cylindrical sample collector slidably fitting within the holder, said collector having a tapered lower end for guiding said collector into said holder, radial window means through the walls of said collector, a ported radial conduit through the walls of said tubular member and said tubular holder adapted to register with said window means when said collector is inserted in said holder, a ported drain conduit extending outwardly through the wall of said tubular member and inwardly through the wall of said holder in communication with the closed lower end thereof, and fishing head means affixed to the upper part of said collector for raising said collector from said holder.

5. Apparatus for collecting earth cuttings from mudflush circulating in a borehole, comprising in combination a tubular member adapted to be connected into a drill string, a tubular holder having an open upper end fixedly carried within the bore of said tubular member co-longitudinally therewith, the outer diameter of said holder

being appreciably smaller than the inner diameter of said bore, whereby a fluid passage is formed within said bore about said holder, a hollow cylindrical sample collector slidably fitting within the holder, a radial window through the walls of said collector, a ported radial conduit through the walls of said tubular member and said tubular holder adapted to register with said window when said collector is inserted in said holder, fishing head means affixed to the upper part of said collector for raising said collector from said holder, and registering first and second guide means respectively carried by said holder and said collector, whereby the engagement of said first and second guide means upon the downward sliding of said collector within the bore of said tubular holder moves said collector to a position wherein the window thereof registers with the ported conduit through said tubular member and holder.

6. Apparatus for collecting earth cuttings from mudflush circulating in a borehole, comprising in combination a tubular member adapted to be connected into a drill string, a tubular holder fixedly carried within the bore of said tubular member co-longitudinally therewith, the outer diameter of said holder being considerably smaller than the inner diameter of said bore, whereby a fluid passage is formed within said bore about said holder, a hollow cylindrical sample collector slidably fitting within the holder, a radial window through the walls of said collector, a ported radial conduit through the walls of said tubular member and said tubular holder adapted to register with said window when said collector is inserted in said holder, fishing head means affixed to the upper part of said collector for raising said collector from said holder, and registering pin and guide means, one of said means carried by said collector and the other by said holder, whereby the engagement of said guide means with said pin means upon the entry of said collector into the bore of the tubular holder causes said collector to rotate until the window thereof is in register with said ported radial conduit through the tubular member and holder as the collector is lowered into the holder.

7. Apparatus for collecting earth cuttings from mudflush circulating in a borehole, comprising in combination a tubular member adapted to be connected into a drill string, a tubular holder fixedly carried within the bore of said tubular member co-longitudinally therewith, the outer diameter of said holder being considerably smaller than the inner diameter of said bore, whereby a fluid passage is formed within said bore about said holder, a hollow cylindrical sample collector slidably fitting within the holder, radial window means through the walls of said collector, ported radial conduit means through the walls of said tubular member and said tubular holder adapted to register with said window means when said collector is inserted in said holder, the outer wall of said tubular member having an annular recess formed therein at the level of the ported radial conduit means, and fishing head means affixed to the upper part of said collector for raising said collector from said holder.

8. Apparatus for collecting earth cuttings from mudflush circulating in a borehole, comprising in combination a tubular member adapted to be connected into a drill string, a portion of the bore of said tubular member being enlarged in diameter, a tubular holder member having an

open upper end, spider means fixedly supporting said holder member within said enlarged bore portion, an annular fluid passage being formed within said enlarged bore portion about said holder, a hollow cylindrical sample collector slidably fitting into the holder, radial windows through the walls of said collector, ported radial conduit means through the walls of said tubular member and said tubular holder adapted to register with said windows when said collector is inserted in said holder, and fishing neck means affixed to the upper part of said collector for raising said collector from said holder.

9. Apparatus for collecting earth cuttings from mudflush circulating in a borehole, comprising in combination a tubular member adapted to be connected into a drill string, tubular holder means fixedly positioned within the bore of the tubular member, said holder means being open at the upper end and having an outside diameter substantially smaller than that of the bore of said tubular member, whereby a flow passage is formed between the outer wall of said holder means and the wall of said bore, drain means in the lower end of said holder means, conduit means through the walls of said tubular member and said holder means in communication between the bore of said holder means and the space outside said tubular means, an elongated hollow cylindrical sample collector fitting slidably within the holder means for insertion and removal through the upper open end thereof, an axially-elongated chamber in said sample collector closed to the space within said drill string, radial window means opening to said chamber through the walls of said sample collector, said window means being adapted to register with the conduit means of said tubular member and holder means when said sample collector is placed therein, and centralizer means carried by said sample collector for centering said sample collector as it passes downwardly through the drill string.

10. Apparatus for collecting earth cuttings from mudflush circulating in a borehole, comprising in combination a tubular member adapted to be connected into a drill string, a tubular holder fixedly positioned within the bore of the tubular member, said holder being open at its upper end and having an outside diameter appreciably smaller than the bore of said tubular member whereby a flow passage is formed between the outer wall of said holder and the wall of said bore, drain means in the lower end of said holder, conduit means through the walls of said tubular member and said holder, an elongated hollow cylindrical sample collector fitting

slidably within the holder for insertion and removal through the upper open end thereof, said collector having a tapered lower end, shoulder means formed on the outer wall of said collector near the upper end thereof arranged to seat on the upper end of said holder, an axially-elongated chamber in said sample collector closed to the space within said drill string, radial window means opening to said chamber through the walls of said sample collector, said window means being adapted to register with the conduit means of said tubular member and container means when said sample collector is supported therein, and centralizer means carried by said sample collector for centering said sample collector as it passes downwardly through the drill string.

11. Apparatus for collecting earth cuttings from mudflush circulating in a borehole, comprising in combination a tubular member adapted to be connected into a drill string, a tubular holder fixedly positioned within the bore of the tubular member, said holder being open at its upper end and having an outside diameter substantially smaller than the bore of said tubular member whereby a flow passage is formed between the outer wall of said holder and the inner wall of said member, drain means in the lower end of said holder, conduit means through the walls of said tubular member and said holder, an elongated hollow cylindrical sample collector fitting slidably within the holder for upward removal therefrom, said collector having a removable tapered lower end, shoulder means formed on the outer wall of said collector arranged to contact the upper end of said holder for supporting the collector therein, an axially-elongated chamber in said sample collector closed to the space within said drill string, radial window means opening to said chamber through the walls of said sample collector, said window means being adapted to register with the conduit means of said tubular member and container means when said sample collector is supported therein, a removable open-top liner carried within said chamber below said window means, and centralizer means carried by said sample collector for coaxially centering said sample collector as it passes downwardly through the drill string.
